United States Patent Office

Des. 183,060
Patented June 17, 1958

183,060

TEXTILE FABRIC OR SIMILAR ARTICLE

Morris Moskowitz, New York, N. Y.

Application November 14, 1957, Serial No. 48,465

Term of patent 3½ years

(Cl. D92—1)

The figure on the drawing is a plan view of a textile fabric or similar article showing my new design.

A design unit is outlined by broken lines and is repeated as indicated.

I claim:

The ornamental design for a textile fabric or similar article, substantially as shown and described.
